UNITED STATES PATENT OFFICE.

JOHN J. CREEDON, OF MOLINE, ILLINOIS, ASSIGNOR TO HERBERT W. COOPER, OF SAME PLACE.

DESIGN FOR A TRACE-CARRIER.

SPECIFICATION forming part of Design No. 33,471, dated October 30, 1900.

Application filed July 5, 1900. Serial No. 22,636. Term of patent 14 years.

To all whom it may concern:

Be it known that I, JOHN J. CREEDON, a citizen of the United States, residing at Moline, in the county of Rock Island and State of Illinois, have invented and produced a new and original Design for Trace-Carriers, of which the following is a specification, reference being had to the accompanying drawings, in which—

- Figure 1 is an isometrical perspective view of a trace-carrier embodying my design. Fig. 2 is a longitudinal sectional view taken on a line parallel with the longitudinal axis of the trace-carrier, but at one side of the center thereof. Fig. 3 is a transverse vertical sectional view taken centrally through the carrier on the line 3 3 of Fig. 1, and Fig. 4 is a plan view of the carrier.

An embodiment of my invention comprises a base-ring or buckle-frame portion 1, above which at each end and at the opposite sides are formed apertures, as indicated at 2 2, 3,

and 4, and with said base-ring is formed integrally a central support, (designated as a whole 5,) from which depend two prongs 6. 25 This support is so conformed that the prongs 6 depend from projections 7, which define the inner sides of relatively large L-shaped openings 8—that is to say, said elevated support outlines at one side of a line extending 30 longitudinally of the carrier three sides of a figure approximately rectangular, and with this the remaining part of the support at the opposite side of the structure is connected by means of a single bar 9, the lower portion of 35 which is bifurcated and united with the base-ring at opposite sides of the strap-opening 3.

I claim as my invention—

The design for a trace-carrier substantially as herein shown and described.

JOHN J. CREEDON.
